UNITED STATES PATENT OFFICE

FRED SCHULTHEISS, OF WOODHAVEN, NEW YORK

DESIGN FOR A WOVEN FABRIC

Application filed July 20, 1928. Serial No. 27,539. Term of patent 7 years.

To all whom it may concern:

Be it known that I, FRED SCHULTHEISS, a citizen of United States, residing at Woodhaven, Long Island, in the county of Queens and State of New York, have invented a new, original, and ornamental Design for a Woven Fabric, of which the following is a specification, reference being had to the accompanying drawing, forming part thereof.

The figure in the drawing is a plan view of a woven fabric embodying my design.

I claim:—

The ornamental design for a woven fabric, as shown.

FRED SCHULTHEISS.
